UNITED STATES PATENT OFFICE.

HOWARD K. KING, OF PHILADELPHIA, PENNSYLVANIA, ASSIGNOR TO
CHAMBERS BROTHERS COMPANY, A CORPORATION OF PENNSYLVANIA.

PUNCHING MECHANISM FOR FOLDING-MACHINES.

No. 801,993.

Specification of Letters Patent.

Patented Oct. 17, 1905.

Application filed January 17, 1905. Serial No. 241,431.

To all whom it may concern:

Be it known that I, HOWARD K. KING, a citizen of the United States, residing at Philadelphia, in the county of Philadelphia and State of Pennsylvania, have invented a new and useful Punching Mechanism for Folding-Machines, of which the following is a specification.

My invention relates to a punching mechanism to be operated in connection with folding-machines.

The object of my invention is to afford simple, convenient, and efficient means for punching holes through separate signatures as the same pass through the folding-machine, my device being adapted to make these holes with such precision as to the location of same that the hole in each signature when folded will register with the hole in every other signature when a number of said signatures are assembled and so accurately that the holes made in a number of signatures by one machine will register with the holes of a number of signatures operated upon by another machine, so that when a large number of said signatures are bound together into a single volume the said holes will all register, so as to form a continuous aperture through the corner of the entire volume for the insertion of a string or wire forming a loop whereby to hang the volume. Such a device is especially useful in connection with the folding and binding of bulky books which it is desired to hang in a convenient place for constant reference—such, for example, as directories.

I accomplish my object by the mechanism illustrated in the accompanying drawings, in which—

Figure 1 is a plan view of a section of an ordinary folding-machine. Fig. 2 is a vertical section on line 2 2 of Fig. 1. Fig. 3 is a horizontal section, enlarged, on the plane indicated by the line 3 3 of Fig. 4. Fig. 4 is a vertical section on the plane indicated by the dotted line 4 4 of Fig. 3. Fig. 5 is a vertical section on line 5 5 of Fig. 2. Fig. 6 is a vertical section on the plane indicated by the dotted lines 6 6 in Fig. 5.

Similar numerals refer to similar parts throughout the several views.

As above stated, Fig. 1 is a plan view of a portion of an ordinary folding-machine of

the same general type as those referred to and described in patents to me No. 667,021, 55 dated January 29, 1901, and No. 667,022, dated January 29, 1901. Reference being made to the descriptions of folding-machines contained in said patents, a further discussion of the details of the folding-machine is 60 thought to be unnecessary in this connection.

Referring to Fig. 1, the rollers 2 and 3 represent the ordinary folding-rollers of the folding-machine, which give the signature its last fold and from which rollers the folded 65 signature is usually dropped into the packing-trough 4.

Where it is desirable to provide a hole or perforation through the corner of the completed volume, which is made up of a number of said signatures, I provide means for puncturing each signature, for example, as the same leaves the last folding-rollers 2 and 3 on its way to the packing-trough 4. For this purpose I provide the rollers 5 and 6, 75 geared together and connected with the gear of roller 3 through the idler-pinion 7, so that said rollers 5 and 6 have a positive rotative relation with the rollers 2 and 3, which are geared together at their other ends by the 80 pinions 8 and 9, respectively.

The rollers 5 and 6 have such a circumferential dimension as will insure the passage of the signature through or between the same with one revolution thereof. In roller 5 is 85 inserted the punch 11, while in roller 6 is inserted a coöperating die 12, these being so located on the rollers with respect to the signature carried between them that the said punch will operate upon the signature 13 in 90 one corner thereof and punch the hole or aperture 14 in said signature 13, as shown in Fig. 5. The said members 11 and 12 are secured in their respective recesses in the rollers 5 and 6 by the set-screws 15 and 16, respectively. (See Fig. 3.) The roller 6 is also provided with a conical-shaped recess 17, concentric with its axis and surrounding the shaft 18, upon which said roller is supported and rotates. This recess 17 extends 100 into the roller 6 sufficiently in depth to connect with the aperture 19 at the rear of the die member 12, so that the punchings may be carried away from the die member through said apertures 19 and 17. Against the aper-tured end of roller 6 is fitted the open end of

conductor 20 for receiving and carrying away said punchings. A deflector 21 may be secured to this conductor 20, so as to project into the aperture 17 and which being stationary will act as a plow or deflector to prevent the clogging of the punchings in said aperture 17. This deflector is preferably inclined to the plane passing through the axis of rotation of the roller 6 for the purpose of increasing its efficiency in deflecting the punchings into said conductor 20.

In the operation of my improved means it is extremely important that the signature is not permitted to slip in its travel through said rollers 5 and 6, since such slipping would cause an error in the position of the aperture punched thereby, so that the same would not register with the apertures in other signatures. By the improvements above described I am able to secure an accurate adjustment of the various parts to secure the desired accuracy in position of punching, and by this means of punching one signature at a time it is possible to produce a volume of unlimited bulk provided with the desired hole after the same has been assembled and bound. The punching mechanism above described is readily adapted to be secured to the ordinary or standard folder and consumes absolutely no additional time in its operation.

As a specific example of the manner in which my invention may be worked I have shown the punching-rollers as working in connection with the rollers giving the last fold to the signature and so that the signature shall be punched after receiving its last fold. It is obvious, however, that without departing from the spirit of my invention this punching mechanism may be differently located. For example, it may be located to operate upon the signature before it receives its last fold, in which case it would only be necessary to provide the punching-rollers with two punches and dies or to so reduce the circumference of the rollers that the punch would operate twice upon the signature passing therebetween in such manner that when the signature has received its last fold the perforations therein will all register. In like manner by keeping in mind the requirement that the perforations of the signature must all register in forming a single

aperture in the signature as finally folded it is obvious that the punching mechanism having the essential features of my invention may be located in different places and operated in connection with different mechanisms of a folding-machine.

While I have shown a rotary punching mechanism as the specific means for punching the signatures, other punching mechanism may obviously be employed with similar result.

My invention, broadly stated, comprises mechanism operating in connection with a folding-machine for punching one or more apertures in each signature as the same passes through said folding-machine.

What I claim is—

1. In combination with a machine for folding signature-sheets, comprising folding-rollers and a reciprocating blade for striking the sheets between said rollers, a punching mechanism having such operative relationship with the folding-machine as to punch a hole through each separate signature as it passes through the folding-machine so that the holes in all the signatures will register.

2. In combination with a machine for folding printed sheets comprising folding-rollers and a reciprocating blade for striking the sheets between said rollers, punching mechanism comprising a second set of rollers provided with punch and die, and geared with the folding-rollers and so positioned as to receive the folded sheets or signatures from the folding-rollers to punch a hole in each signature so that the holes in a number of signatures when bound together, will register.

3. In combination with a folding-machine, comprising a pair of folding-rollers, a pair of additional rollers having a geared relationship therewith and provided with a punch and die for operating upon the signature carried therethrough, the die-roller provided with an aperture, communicating with the die, for receiving the punchings, conducting means, leading from said aperture, for carrying the punchings therefrom and a deflector for delivering the punchings from the roller to said conducting means.

HOWARD K. KING.
